UNITED STATES PATENT OFFICE.

WILLIAM P. VARNEY, OF CHICAGO, ILLINOIS, ASSIGNOR TO HYDRAULIC PRESS BRICK COMPANY, OF ST. LOUIS, MISSOURI, A CORPORATION OF MISSOURI.

MACHINE FOR ORNAMENTING BRICK.

1,202,252.

Specification of Letters Patent. Patented Oct. 24, 1916.

Application filed January 9, 1915. Serial No. 1,329.

To all whom it may concern:

Be it known that I, WILLIAM P. VARNEY, a citizen of the United States, residing at Chicago, in the county of Cook and State 5 of Illinois, have invented certain new and useful Improvements in Machines for Ornamenting Brick, of which the following is a specification.

This invention relates to brick making 10 machinery, and more particularly to that class of brick machinery adapted to produce rough texture brick.

The primary object of this invention is to provide a machine of the character set forth 15 adapted to stand heavy work and produce fine quality brick.

A further object of this invention is to construct a machine of the character set forth as to enable its installation in close 20 proximity to the column forming machine.

A further object of this invention is to provide means for roughening the face of a clay column and to provide automatic means for maintaining the depth of the cut into 25 the clay, insuring uniformity of design in the finished article.

A still further object of this invention is to provide a machine of the character described adapted to operate with the minimum 30 of working parts and the minimum amount of power.

With these and other objects in view as will hereinafter appear this invention consists in the peculiar arrangement and combination of the various related elements hereinafter described and more particularly set forth in the appended claims.

Referring to the drawings wherein similar reference characters indicate similar 40 parts wherever used, Figure 1 is a top plan view of the machine; Fig. 2 is a side elevation thereof; Fig. 3 is a section on line 3—3 of Fig. 1; Fig. 4 is a detail section on line 4—4 of Fig. 1 looking in the direction 45 of the arrow of one of the marking disks and its driving mechanism; Fig. 5 is a detail fragmentary plan view of one of the marking disks.

The numeral 6 designates the mouth of 50 any suitable clay column forming machine used in brick making plants and constituting no portion of my invention. Supported upon rollers 7 is an endless belt or apron

8 adapted to receive the clay column as it issues from the mouth 6. The rollers 7 are 55 carried by axles 9, mounted in bearings 10—11 supported by angle irons 12—13. Extending from the angle iron 12 are uprights 14, 15 and 16, and from angle iron 13 extend uprights 17 and 18. Uprights 14, 60 16, 17 and 18 support side members 19—20 connected by cross pieces 21—22 and 23. The angle iron 12 carries links 24—25 pivoted thereto by bolts 26—27 and pivotally connected to a longitudinal bar 28 by bolts 65 29—30. A similar construction comprising links 31—32 pivoted at 33—34 and connected at 35—36 to a bar 37 is mounted on the angle iron 13. The bars 28—37 are connected intermediate their ends by means of cross 70 pieces 38—39. At the inner end of the machine the links 25—32 are connected by a shaft 40 carrying a roller 41 adapted to bear upon the top of the clay column passing thereunder. Each of the cross pieces 75 38—39 supports a screw-threaded stub shaft 42—43 and rotatably mounted upon the respective cross pieces by means of washers 46—47 each of which is locked in place by superposed nuts 48 and 49. Bearings are 80 provided, the one for the shaft 42 being on the side rail 20, and designated by the numeral 52, and a similar bearing 53 on the side rail 19. Above the bearings each shaft is provided with a bevel gear 54—55 splined 85 to the respective shafts by splines 56—57 in such a manner as to permit the shafts to move vertically.

Below the supporting cross piece each of the shafts 42—43 carries a marking disk 90 which, as shown, comprises a disk faced with a sheet metal 60—61 from which prongs or teeth 62 have been struck out in concentric series around the face thereof. The shafts 42—43 pass through openings 38' and 39' in 95 the cross members 38 and 39 respectively, the supporting washers 46—47 resting upon the edges of the said openings of each cross bar. The provision of a screw threaded shaft 42 or 43 with the lock nuts 48—49 permits of adjustment of the shaft relative to the distance above the clay stream, thus allowing for wear of the teeth 62 upon the disks 60—61.

A shaft 63 provided with a sprocket wheel 105 64 and pulley 65 for suitable drive attach-

ments for outside power is mounted in bearings on the uprights 14 and 17 and carries an intermediate bevel gear 66 meshing with a bevel gear 67 on a shaft 68 mounted in bearings 69—70 on the side rail 20 and provided with a second bevel gear 71 meshing with the drive gear 54 on the stub shaft 42. A second shaft 72 carries a bevel gear 73 which meshes with the gear 54. This shaft is mounted in bearings 74—75 upon the cross bars 22—23 and extends at an angle across the machine body to the gear 55 of the shaft 43 where it is provided with a bevel gear 76 meshing with the gear 55, thus causing the first disk to rotate in one direction and the other disk to rotate in another direction.

Mounted on the upright 15 is a shaft 77 having a plate 78 provided with teeth 79 similar to the teeth 62 of the plates 60—61. A spring 80 forms a cushion for the plate 78 to which rotary motion is imparted by an outside source of power connected to the pulley 81 on the shaft 77.

A finishing roller 82 for the side of the column is pivotally mounted at 83 upon an angle iron 84 and is adapted to be held against the side of the clay column by means of a weight 85 attached to the iron 84 by a cord 86 traveling over a guide 87. A finishing roller for the top of the clay column is located at the discharge end of the machine and comprises a roller 88 upon a shaft 89 carried by two L members 90 placed in reverse position and pivotally mounted at 92—93 upon the side rails 19—20 in such a manner as to cause the roller to normally exert pressure downwardly by reason of its own weight, notches 94 being provided in the ends of the members 90 to support suitable weighting bars should it be necessary.

The operation of the device is as follows: The clay column extending from the column forming machine travels over the apron 8 and under the roller 41 to the rapidly revolving plate 78 which, by means of the teeth 79, tears up and roughens the face of the column forming a novel, distinctive and ornamental design upon the clay. The side of the column is finished by the roller 82. The top of the column is similarly roughened and ornamented by the teeth of the two plates 60, 61. Inequalities in the height of the clay stream cause the roller 41 to be raised or lowered, causing a corresponding movement of the parallel bars 28—37, thus raising or lowering the cross members 38—39 and the shafts 42 and 43 and the roughening disks carried thereby, thus keeping the depth of cut of the teeth at substantially the same, insuring uniformity of design. The longitudinal movement of the cross bars 38—39 in making either an up or down movement due to the link bars 28—37 is compensated for by the spaces 38'

and 39' which allow the respective cross bars to slide beneath the washers 46 and 47 while raising the same and correspondingly the shafts 42—43. The top of the clay column is finished by the roller 88.

As many changes could be made in the above construction and many apparently widely different embodiments of my invention could be made without departing from the scope thereof, it is intended that all matter contained in the above description or shown in the accompanying drawing shall be interpreted as illustrative and not in a limiting sense.

Having thus described my invention what I claim as new and desire to secure by Letters Patent is:

1. In a machine for ornamenting brick, the combination with means for conveying a clay column, of a substantially flat rotary marking device located in position to contact a surface of the column, and means for rotating the marking device in a plane whose axis is substantially perpendicular to said surface of the clay column.

2. In a machine for ornamenting brick, the combination with means for conveying a clay column, of a substantially flat rotary marking disk located in position to contact a surface of the column, and means for rotating the marking disk in a plane whose axis is substantially perpendicular to said surface of the clay column.

3. In a machine for ornamenting brick, the combination with means for conveying a clay column, of a plurality of substantially flat rotary marking devices located in position to contact a surface of the column, and means for rotating the marking devices in a plane whose axis is substantially perpendicular to said surface of the clay column.

4. In a machine for ornamenting brick, the combination with means for conveying a clay column, a substantially flat rotary marking disk provided with a plurality of projecting teeth on one face thereof, said disk being located in position for the teeth to contact with a surface of the column, and means for rotating the disk in a plane whose axis is substantially perpendicular to said surface of the clay column.

5. In a machine for ornamenting brick, the combination with means for conveying a clay column, a marking device in position to contact with the surface of the column, and means controlled by the thickness of the column for moving said marking device toward and away from the column.

6. In a machine for ornamenting brick the combination with means for conveying the clay column, a marking device located in position to contact with the surface of the column, a device adapted to rest on the surface of the column, and connections be-

tween the said device and said marker whereby the position of the device controls the position of the marker.

7. In a machine for ornamenting brick, 5 the combination with means for conveying a clay column, a marking device located in position to contact with the surface of the column, a roller contacting with the surface of the column and connection between the 10 roller and the marking device whereby movement of the former will move the latter toward and away from the column.

8. A brick scratcher comprising a support for a clay bar a member disposed adjacent the clay bar, a suitable supporting framework for said member, a series of projections on said member, and means for imparting movement to said member to move said projections in paths concentric with 20 each other across the face of the clay bar.

9. Apparatus of the character described,

comprising a guideway for the moving bar or column of clay, and rotary members overhanging the guideway from opposite sides and each having a plurality of depending 25 scratching points or pins, substantially as described.

10. Apparatus of the character described, comprising a guideway for the moving bar or column of clay, and rotary members overhanging the guideway from opposite sides and each having a plurality of depending 30 scratching points or pins, together with a surfacing roller journaled transversely of the guideway beyond the rotary members, 35 substantially as described.

In testimony whereof I affix my signature in presence of two witnesses.

WILLIAM P. VARNEY.
